UNITED STATES PATENT OFFICE.

HENRY E. WAITE, OF NEW YORK, N. Y.

DESIGN FOR AN OZONE-GENERATOR.

SPECIFICATION forming part of Design No. 32,526, dated April 17, 1900.

Application filed March 19, 1900. Serial No. 9,342. Term of patent 7 years.

To all whom it may concern:

Be it known that I, HENRY E. WAITE, a citizen of the United States, residing in the city, county, and State of New York, have invented and produced a new and original Design for Ozone-Generators, of which the following is a specification, reference being had to the accompanying drawing, forming part thereof.

In the accompanying drawing my new design is shown in perspective.

The essential features of the new design comprise a spherical body mounted on a base, having a cap at the upper portion, opposite lateral extensions from the body, and a projection to which is attached a cylinder. Thus, in the drawing, A is the spherical body, mount-

ed on the base B and having the cap C. Projecting from opposite sides of the body are the lateral extensions D D. There is also a projection E extending from the body to the cylinder F, from which extends the tube G.

What I claim is—

The design for an ozone-generator, substantially as shown and described.

In testimony whereof I have signed my name to this specification in the presence of two subscribing witnesses.

HENRY E. WAITE.

Witnesses:

W. H. WOODHULL,
THOMAS D. BAKER.
